UNITED STATES PATENT OFFICE.

THOMAS NELSON, OF PENDLETON, OREGON.

DESIGN FOR A PRINTER'S JOB-CASE.

SPECIFICATION forming part of Design No. 27,549, dated August 17, 1897.

Application filed December 19, 1896. Serial No. 616,341. Term of patent 14 years.

To all whom it may concern:

Be it known that I, THOMAS NELSON, a citizen of the United States, residing at Pendleton, in the county of Umatilla and State of Oregon, have invented and produced a certain new and original Design for Printers' Job-Cases; and I do declare the following to be a full, clear, and exact description of the invention, such as will enable others skilled in the art to which it appertains to make and use the same.

My invention relates to a new design for a printer's job-type case.

The principal feature of my design consists in the arrangement of the compartments in the case, all of those at the right end being small, as well as nearly all of those along the border, while most of the intervening compartments are much larger, some being true squares and others elongated rectangular figures, giving to the case as a whole the appearance shown in the drawing. The raised front edge of the case is corrugated, giving it a wavy outline.

My invention relates particularly to a case as illustrated in the accompanying drawing, in which the figure is a perspective view of a job-type case embodying my design.

The relative proportions and configuration of the compartments are fully shown in the drawing and will be readily understood without further description.

It will be noticed that the compartments for the "lower-case" letters are at the left side of the case, while the compartments for the "capitals" are at the right and at the top of the case, and at the bottom of the capital-case there is a line or series of narrow boxes or compartments designed for containing rules and dashes. This arrangement makes a new and original design in cases for job-printers' use.

Having thus fully described my design, what I claim, and desire to secure by Letters Patent of the United States, is—

The design for a printer's job-case, substantially as herein shown and described.

In testimony whereof I hereunto affix my signature in presence of two witnesses.

THOMAS NELSON.

Witnesses:

Mrs. THOMAS NELSON,
I. NEWTON RICHARDSON.
